(57) **CLAIM**

The ornamental design for a paper tray, as shown and described.

DESCRIPTION

FIG. 1 is a top isometric view of a paper tray, according to a first embodiment;

FIG. 2 is a front view thereof; the rear view being identical;

FIG. 3 is a bottom isometric view thereof;

FIG. 4 is a side view thereof; the other side being identical;

FIG. 5 is a top view thereof; and

FIG. 6 is a bottom view thereof;

FIG. 7 is a top isometric view of a paper tray, according to a second embodiment;

FIG. 8 is a front view thereof; the rear view being identical;

FIG. 9 is a bottom isometric view thereof;

FIG. 10 is a side view thereof; the other side being identical;

FIG. 11 is a top view thereof; and

FIG. 12 is a bottom view thereof;

FIG. 13 is a top isometric view of a paper tray, according to a third embodiment;

FIG. 14 is a front view thereof; the rear view being identical

FIG. 15 is a bottom isometric view thereof;

FIG. 16 is a side view thereof; the other side being identical;

FIG. 17 is a top view thereof; and

FIG. 18 is a bottom view thereof;

FIG. 19 is a top isometric view of a paper tray, according to a fourth embodiment;

FIG. 20 is a front view thereof; the rear view being identical

FIG. 21 is a bottom isometric view thereof;

FIG. 22 is a side view thereof; the other side being identical;

FIG. 23 is a top view thereof; and,

FIG. 24 is a bottom view thereof.

1 Claim, 24 Drawing Sheets
